UNITED STATES PATENT OFFICE

THOMAS LITWILLER, OF TREMONT, ILLINOIS.

WIRE FENCE.

No. 798,685

Specification of Letters Patent.

Patented Sept. 5, 1905.

Application filed September 14, 1903. Serial No. 173,058.

To all whom it may concern:

Be it known that I, THOMAS LITWILLER, a citizen of the United States, residing at Tremont, in the county of Tazewell and State of Illinois, have invented certain new and useful Improvements in Wire Fences; and I do hereby declare that the following is a full, clear, and exact description of the invention, which will enable others skilled in the art to which it appertains to make and use the same.

This invention has reference to wire fencing or wire-fence fabrics.

It comprises in its structure a fence similar to that shown in my application filed November 15, 1902, Serial No. 131,401, wherein a fabric is formed of body-wires and selvage-strands, and connected or intertwined with the body-wires and selvage-strands are stay-wires that bear diagonally to the body of the fence and are intertwined with the selvage and body wires where they intersect alternately over and under. In the application referred to the twists of the stays with the body and selvage wires are always in the same direction—that is, the twist is a continuous right or left twist.

The object which I have in view in the present invention is to construct a fence fabric having stays bearing diagonally to the body of the fence and at the intersection of the body and selvage wires intertwined or interlocked therewith with a right-and-left twist or vice versa.

Further objects and aims of the invention will appear from the following specification, claim, and accompanying drawings, in which—

Figure 1, drawn to a small scale, shows a strip of fence embodying my improvements as it appears when placed in the field. Fig. 2, drawn to a larger scale, shows more clearly the detail construction of the fence.

The fence comprises what will be hereinafter known as the "selvage-wires" 1 and the "body-wires" 2, arranged at suitable intervals apart from each other intermediate the selvage-wires to present a uniform or graduated mesh, as may be desired. 3 indicates stays, preferably of wire, spaced at suitable intervals apart and adapted to be intertwined or interlocked with the selvage and body wires, which together comprise my improved fencing.

The selvage-wires are shown as single strands; but it is to be understood that a suitable cable-strand may be employed and the invention carried out as herein provided.

As indicated, the stays 3 bear diagonally

across the body and selvage wires. At the intersection of each of above-said wires the stays are interlocked therewith—that is, the stays are gripped, together with the body and selvage wires, at 4 to form the parallel plain portion of the stay and body or selvage wires and the action of the shuttle, spool, or coiler carrying the stay or engaging the stay and body wire or selvage is to intertwist or interlock the wires to form a right-and-left (or left-and-right) twist upon opposite sides of the gripped or plain portions. The nature of the twist or lock of the wires is to produce a twist which shall be longer upon one side of the gripped or plain portion 4 than upon the opposite side, as seen in Fig. 2. In carrying out the invention the stay-wires are directed alternately over and under the intersecting strand-wires, so as to form an interlock with said strands first in a direction right and left and alternately left and right. This alternate arrangement is accomplished by rotating the shuttle or spools first in one direction and then in an opposite direction. 80

Where the ends of the stays leave the spools or shuttles or are cut after completing their required interlock, the end of such stay is directed longitudinally along the selvage and in juxtaposition thereto, as at 5. 85

A better understanding of the diagonal of the stay-wires and their alternate interlocking in reverse directions with the intersecting strand-wires will be had from the following: Follow the complete stay in Fig. 1 (indicated 90 as 1) leading from the lower selvage-wire 1. The said stay is interlocked with the selvage-wire for a portion of its length. It is then led diagonally and in advance of its interlock with said selvage-wire to the adjacent intermediate strand-wire 2 and interlocked therewith in a reverse direction to the interlock of the selvage-wire. The stay-wire is then led diagonally to the next adjacent intermediate strand-wire in manner as before and continued to be so led until it coincides with the upper selvage-wire. As before stated, the interlocking of the stay-wire with the intersecting strand and selvage wires being alternately right and left and left and right, in 105 the completion of a stay the same bears diagonally from selvage to selvage-wires and forms an arc between their ends, substantially as seen in Fig. 1.

It is understood, as in the application referred to, to manufacture a fencing which may be produced at a minimum cost and de-

livered from the machine operated to produce a continuously-made fabric.

I am aware that the interlocking or intertwisting of one or more wires having a right-and-left twist is not new; but this is in a fabric having a hexagonal mesh where the body-wires are fed longitudinally and in a sinuous line; but I do not know of a stay-fence where the stays are carried diagonally across the fabric and interlocked with the body and selvage wires at their intersection which produces a fabric having substantially a rectangular mesh.

The operation of a machine to produce such a fabric as herein shown is vastly different to those which produce a hexagonal mesh, and neither could be made upon the other machine. Likewise in the application referred to the mode of interlocking the diagonal stay is entirely different from those which produce a continuous twist all in the same direction. As the stays bear diagonally across the fabric so are the twists measured along the wires in the same longitudinal direction. By directing the stays diagonally and forming an interlocked twist at the intersection of the strand-wires I form a mesh with the short

sections of stays between the wires appearing in break-joint fashion and providing a truss for the portions of the strand-wires intermediate the stays leading in opposite directions therefrom, all of which aids in strengthening the fence and produces a neat design.

Having thus fully described my invention, what I claim, and desire to secure by Letters Patent of the United States, is—

A wire fence composed of body-wires and selvage-wires, of stay-wires extending obliquely across the body-wires from selvage-wire to selvage-wire, adjacent stays extending approximately parallel and at each succeeding point of intersection with the selvage and body wires intertwined therewith by a right-and-left intertwist and alternately by a left-and-right intertwist and having the twists measured along the body and selvage wires in the same direction.

In testimony whereof I affix my signature in presence of two witnesses.

THOMAS LITWILLER.
